UNITED STATES PATENT OFFICE.

JOSEPH M. COFFEY, OF NEW YORK, N. Y., ASSIGNOR TO CHAMBERS VALVE COMPANY,
OF NEW YORK, N. Y., A CORPORATION OF NEW YORK.

THROTTLE-VALVE.

1,215,488.

Specification of Letters Patent. Patented Feb. 13, 1917.

Application filed May 19, 1916. Serial No. 98,666.

To all whom it may concern:

Be it known that I, JOSEPH M. COFFEY, a citizen of the United States, residing at New York, in the county of New York and State 5 of New York, have invented certain new and useful Improvements in Throttle-Valves, of which the following is a specification.

This invention relates to improvements in throttle valves and more particularly to 10 throttle valves adapted for use on locomotive boilers.

One of the objects of the present invention is to provide a simple and practical throttle valve in which the amount and rate of flow 15 of steam passing therethrough may be more easily and desirably controlled. A further object is to provide a throttle valve which will be reliable and efficient in use and operation and in which corresponding movements of the valve away from its seat will first cause a progressively increasing area of 20 opening through which the steam may pass followed by a progressively decreasing rate of increase of area.

Other objects will be in part obvious from the annexed drawings and in part indicated in connection therewith by the following 25 analysis of this invention.

This invention accordingly consists in the 30 features of construction, combination of parts and in the unique relations of the members and in the relative proportioning and disposition thereof, all as more completely outlined herein.

To enable others skilled in the art so fully 35 to comprehend the underlying features thereof that they may embody the same by the numerous modifications in structure and relation contemplated by this invention, drawings depicting a preferred form 40 have been annexed as a part of this disclosure, and in such drawings, like characters of reference denote corresponding parts throughout all the views, in which—

Figure 1 is a transverse vertical sectional 45 view of the valve and valve seat, the actuating mechanism and associated parts of the valve being omitted for the sake of clearness;

Fig. 2 is a side perspective view of the 50 valve.

Referring now to the drawings in detail, 5 denotes a valve member which is preferably cylindrical in form having a central

opening 6 therein and in which the valve

stem (not shown) is adapted to be mounted. The cylindrical part of this member is provided with a projection having a ground beveled or angularly disposed edge 7 adapted to coact with a valve seat 8. Projecting 60 downwardly and preferably at four equally distant points about the circumference of the valve are guide wings 10 formed integral with the valve and coacting with the inner surface of the throttle box or valve seat in 65 the usual manner. The walls of the valve member between the wings are cutaway or are shaped terminating in squared portions 12, as shown more clearly in Fig. 2. The length of the base of the arcs is much greater 70 than their height, or, in other words, the arcs are relatively broad. This wall may be of any desired shape or curvature, but a curve of uniform radius on the cylindrical surface of the valve is preferable, it being 75 understood that the outer surface of this wall is adapted to closely fit the inner surface of the valve seat or throttle box.

If the valve is raised but a quarter of an 80 inch a relatively small segment of each arch will be presented to the passage of steam therethrough. If the valve is raised a half inch, approximately three times the area of valve opening will result. A further raising 85 of the valve however will produce a progressively decreasing rate of increase of area through which the steam may pass until the squared corners 12 at the end of the arc are reached, after which the rate of increase will be substantially uniform. Thus a quarter 90 inch lift will produce an area of about eleven units, two quarters a total of about 46.7 units, three quarters a total of about 80.5 and a fourth quarter about 120.4 units with a cutaway part of substantially uniform 95 radius. This may be varied of course by changing the shape of the opening. This form of valve is particularly desirable where light movement is necessary, as when slowly backing or in coupling cars.

While only sufficient parts of the throttle valve mechanism are herein shown to fully illustrate the present invention, it is to be understood that the features thereof may be combined with substantially any form of 100 throttle valve of this broad general character now in use. By constructing a valve in this way a more desirable control of the passage of steam is obtained.

The invention is simple and practical in 110

construction, reliable and efficient in use and operation and does accomplish, among others, all of the objects and advantages herein set forth.

- 5 Without further analysis, the foregoing will so fully reveal the gist of this invention that others can by applying current knowledge readily adapt it for various applications without omitting certain features that, 10 from the standpoint of the prior art, fairly constitute essential characteristics of the generic or specific aspects of this invention, and therefore such adaptations should and are intended to be comprehended within the 15 meaning and range of equivalency of the following claim.

Having thus described my invention what I claim as new and desire to secure by Letters Patent is—

- 20 In a throttle valve, in combination, a valve seat, a valve member of general cylindrical shape having an outwardly projecting angu-

larly disposed seating surface near its upper part adapted to coact with said valve seat, a plurality of guides associated with the valve member adapted to center the valve with respect to the valve seat, the valve member comprising cut away walls between the guides forming relatively broad arcs in said walls whereby the area of the passage between the valve and the valve seat is progressively increased for uniform movement of the valve during the first part of the opening thereof, said valve member being provided with a central opening having a 30 valve seat associated therewith within which a valve stem may be loosely mounted.

In testimony whereof I affix my signature in presence of two witnesses.

JOSEPH M. COFFEY.
